Robert B. Clark, Washington, D. C., assignor to
Hospital Picture Service Corporation, Cam-
bridge, Mass., a corporation of Massachusetts

Application June 30, 1950, Serial No. 10,888

Term of patent 3½ years

(Cl. D61—1)

To all whom it may concern:

Be it known that I, Robert B. Clark, a citizen of the United States, residing at 5028 Massachusetts Avenue N. W., Washington, D. C., have invented a new, original, and ornamental Design for a Camera, of which the following is a specification, reference being made to the accompanying drawing, forming a part thereof.

Fig. 1 is a top plan view of a camera, showing my new design;

Fig. 2 is a front elevational view of the camera;

Fig. 3 is an end view;

Fig. 4 is a bottom view; and

Fig. 5 is a rear view.

I claim:

The ornamental design for a camera, substan-
tially as shown.

ROBERT B. CLARK.
